[57] CLAIM

The ornamental design for a linear multilamp photoflash unit, as shown and described.

DESCRIPTION

FIG. 1 is a front elevational view of a linear multilamp photoflash unit showing our new design;

FIG. 2 is a side elevational view, the opposite side being a mirror image thereof;

FIG. 3 is a rear elevational view thereof; and

FIG. 4 is an end elevational view, the opposite end being identical thereto.
